UNITED STATES PATENT OFFICE

132,361

DESIGN FOR A GRANDSTAND

Gavin Hadden, New York, N. Y.

Application February 16, 1940, Serial No. 90,312

Term of patent 14 years

To all whom it may concern:

Be it known that I, Gavin Hadden, a citizen of the United States, residing at New York city, county of New York and State of New York, have invented a new, original, and ornamental Design for Grandstands, of which the following description, in connection with the accompanying drawing, is a specification.

Fig. 1 is a perspective view of a grandstand showing my new design.

Fig. 2 is a top plan view thereof drawn to a smaller scale; and

Fig. 3 is a rear elevational view on the scale of Fig. 2.

The essential feature of the new design consists in the fact that the outer edge of the grandstand is extended outward in rectangular steps which approximate a bi-laterally symmetrical trapezoid in plan as shown in Fig. 1, and is higher at or near the center and decreases in height towards the ends, being also approximately trapezoidal in the front and rear elevations, as shown in Fig. 3.

I claim as my invention:

The ornamental design for a grandstand, as shown and described.

GAVIN HADDEN.
